REFINISHING DEVICE

Filed April 8, 1929

UNITED STATES PATENT OFFICE

JOHN V. BUECKERMAN, OF DENVER, COLORADO

REFINISHING DEVICE

Application filed April 8, 1929. Serial No. 353,508.

My invention relates to a device for refinishing valves and valve seats, particularly poppet valves and poppet valve seats used in internal combustion engines.

5 Objects of the invention are to utilize the valve seat for holding the device when refinishing the valve and to use the valve as a guide when refinishing the seat. Thus both the valve and its seat may be refinished while 10 the valve is in position.

Another object is to provide a simple, portable device for the above purposes.

Still other objects reside in novel details of construction and in novel combinations and 15 arrangements of parts, which will more fully appear in the course of the following description.

The same characters designate similar parts in the several views.

20 Figure 1 is a vertical section of a portion of an internal combustion engine, showing the present device in operative position.

Figure 2 is a view similar to Figure 1, but partly in elevation and showing locking 25 means hereinafter to be described.

Figure 3 is a section taken on the line 3—3 of Figure 1.

Figure 4 is a perspective view of the shell 30 of the present device.

Figure 5 is a section taken on the line 5—5 of Figure 2.

Figure 6 is a broken elevation of a detail 35 hereinafter to be described.

Referring more specifically to the drawings, the reference numeral 5 designates generally an internal combustion engine having a poppet valve seat 6 and a guide-way 7 for the stem of a poppet valve.

The numeral 8 designates the poppet valve, 40 which has a stem 9 disposed in the guide-way 7. The valve has a face 10 that engages the valve seat 6 during the operation of the engine. The valve shown has a groove 11 in its head, as is customary with many poppet 45 valves.

My refinisher comprises a shell shown in perspective in Figure 4. The shell has a truncated, conical body portion 12 that tapers to a hollow, threaded extension 13 at one end. The opposite end merges into an annulus 14 50 apertured at 15. The threaded extension 13 and conical body 12 are slit as seen at 16.

The conical body portion 12 is lined with an emery or abrasive paper or fabric 17. The ends of the abrasive material are inserted into channel-shaped members 18, shown in Figure 6, the sides of which are crimped together to hold the abrasive material.

The abrasive material 17 is placed in the conical body 12 and the clamps 18 at the ends 60 are inserted in the same portion of the slit 16, as best seen in Figure 3. By crowding the clamps 18 into the same part of the slit, they are firmly held in place.

The exterior of the body member 12 is covered with similar emery or abrasive material 19. Clamps 20 at the ends of the material 19 65 are similar to the clamps 18. The clamps 20 are crowded into another portion of the slit 16 to firmly hold the material 19 in place. 70

A nut 21 is screwed on the threaded extension 13. The interior diameter of the nut is preferably slightly less than the exterior diameter of the threaded extension 13, so that the separated sections of the extension 13 may 75 be drawn together by the nut.

The nut has a rim 22 interiorly beveled to engage the edge of the abrasive material on the outer surface of the body 12 when the nut is screwed home, to assist in holding the abrasive material in place.

It is preferred to make the bore of the threaded extension of larger diameter than that of the stem of any valve now used in internal combustion engines and to place an 80 adapter 23 in this extension. Adapters having different sized bores may then be used for different sized stems.

Means for rotating the valve has been indicated in Figure 1. This means comprises 85 90

a ring 24 having a pivoted handle 25 for operating it. The ring is adapted to be inserted in the groove 11. When it is desired to rotate the valve and refinisher simultaneously a key 5 26 may be inserted through the apertures 15 of the annulus 14 and through the ring 24. The key thus locks the valve and refinisher together.

The operation of the device will now be explained. When it is desired to refinish the 10 face of the valve, the device is seated on the valve seat as shown in Figure 1 and held in place by hand. The valve is then rotated relative thereto, and at the same time its face is 15 depressed against the abrasive material on the interior of the shell.

This operation refinishes the face of the 20 valve while it is in its normal operative position.

It is thought apparent that the valve may 25 be held stationary by the means shown and the face of the valve and the valve seat simultaneously refinished by rotating the present device by hand or otherwise.

To refinish the seat, the present device is 30 placed upon same with the valve in position, as shown in Figure 2. The valve and shell are then locked together by the key 26. By rotation of the valve and device by the handle 25, the abrasive material 19 refinishes the seat. 35 The valve and its stem in this instance act as a guide.

When the exterior diameter of the extension 40 is slightly greater than the interior diameter of the nut 21, the nut is then used to clamp the sections of the extension upon the 45 adapter, to hold the latter in place.

The advantage of refinishing the valve 50 while it is in place and the advantage of using the valve and stem as a guide when refinishing the seat are that common inequalities of the valve and seat will not be disturbed, and 55 they will be refinished alike.

My device, therefore, not only refinishes, 60 but after refinishing the valve and seat fit better than they did before and much better 65 than if the valve and seat were refinished without any relation to each other.

Where the valve head does not have a 65 groove 11 or other depression or depressions, such may be made in the valve head, or the valve may be rotated by any other suitable means while the present device is held against the face thereof.

What I claim and desire to secure by Letters Patent is:

1. A refinishing device, comprising a body 70 adapted for engagement with a valve seat, an abrasive member on the body, an adapter on 75 the body, to fit around a stem of a valve co-operative with the seat, and a member on the body adapted to clamp in one operation the abrasive member and the adapter to the body.

2. A refinishing device comprising a grinding-element having an outer grinding face

adapted for engagement with a valve-seat, and an inner face adapted for frictional engagement with a valve, the element having aligned apertures for the application of a key, and an operating-element including a ring 70 adapted to engage in a slit of the valve, and a key extending through the ring and into the apertures of the grinding-element.

In testimony whereof I have affixed my signature.

JOHN V. BUECKERMANN.
